Attorney.

UNITED STATES PATENT OFFICE.

ANDREW STRAND, OF MINNEAPOLIS, MINNESOTA.

VISE.

Application filed May 14, 1919. Serial No. 296,969.

To all whom it may concern:

Be it known that I, ANDREW STRAND, a citizen of the United States, residing at Minneapolis, in the county of Hennepin and 5 State of Minnesota, have invented a new and useful Improvement in Vises, of which the following is a specification.

My invention relates to vises, which are commonly used in various shops, and is particularly adapted for use where it is desired 10 to quickly remove the face plates from the main jaws of the vise so that other face plates can replace the same for various kinds of work. In using a vise, it is often desirable to remove the face plates of the gripping jaws of the vise so as to more conveniently hold a piece or article between the vise jaws and use different sets of faces on the gripping jaws of the vise so as to hold the 15 article in the vise in the most convenient and practical manner, but it is an essential feature of my invention that the face plates of the gripping jaws be quickly removable and still firmly held when in place on the 20 jaws of the vise.

It is also a feature of my invention to provide a vise with one of its jaws pivoted in relation to the vise proper, so that different jaws can be turned to extend at an angle to 25 the other jaw of the vise and a means for holding this jaw rigidly in this angular position so that an article can be clamped between the jaws of the vise, while their faces are at an angle to each other and the jaw 30 which is set at an angle being held rigid against rotation while gripping the article between the gripping jaws of the vise. This is an important feature, as it overcomes and prevents the movement of the pivoted jaw 35 while holding any article between the vise jaws.

The peculiar arrangement and combination of elements will be clearly set forth in the specification and claims.

40 In the drawing forming part of this specification:

Figure 1 is a side elevation of my vise.

Figure 2 is a plan view of the vise.

Figure 3 is a plan view of a detail of one 45 of the jaws of the vise, a portion of which is broken away.

Figure 4 is a back view of one of the face plates of the vise.

Figure 5 is a side view of a variation of 50 face plate used on my vise.

Figure 6 is a section on the line 6—6 of Figure 3.

The vise A has a stationary portion 2 and a movable portion 3, the general construction of which is common in the ordinary 60 bench vise. The stationary portion is formed with a base portion 4, by which it is adapted to be secured in the ordinary manner to a bench, or other place where it is desired to rigidly hold the vise for use.

The portions 2 and 3 of the vise are formed with upwardly projecting main jaw portions 5 and 6, respectively, to which are removably or detachably secured a pair of face or gripping plates 7. The gripping 70 faces 8 of the plates 7 can be made serrated or roughened, or of any suitable shape to hold various articles in the vise, and in some instances, it is desirable to have the faces 8 smooth and highly polished, so as not to injure the article gripped in the vise. Each of the face plates 7 are formed with an elongated projection or tongue portion 9, which projects from the inner face 10, having curved ends 11 which terminate a short distance from the ends of the face plate, and holding pins 12 are formed projecting from the tongue 9, which are formed with a beveled end 13 and a notch 14. The pins 12 of the plate 7 are positioned near the ends of 80 the projecting tongue 9, with the notches 14 on the inner side of each of the pins so that when the plates 7 are attached to the members 5 and 6 of the vise A, the notches 14 will be engaged by the spring operated 85 catches or bolts 15. The catches 15 are slidably held in the passageway 16, formed in the members 5 and 6, and are resiliently held spaced apart by the coil spring 17. The catches 15 are formed with engaging beveled 90 ends 18, which are adapted to engage in the notches 14 and which are similar in shape to the notches 14. The body portion of the catches 15 are cut away at 19 to receive the pins 20, which hold the spring catches 15 95 from being forced too far apart by the coil spring 17 when the pins 12 of the face plates are removed from the openings 21 in the members 5 and 6, the catches being limited by the shoulders 22, which engage against 100 the pins 20 and form a stop to hold the catches 15 in place.

The pins 20 also hold the catches from 105 rotating in the opening 16, in this manner always causing the beveled ends 18 to engage 110

properly with the notches 14 of the pins 12.

The faces 23 of the members 5 and 6, against which the backs 10 of the face plates engage, are formed with a recess 24 of a similar size and shape as the projecting tongue 9 on the face plate 7, so as to receive the tongue or projecting portion 9 with a close fit, to hold the same against heavy thrusts and strains when the face plates are 10 in position on the members 5 and 6 and in use. In this manner practically no strain is transmitted to the holding pins 12 and the catches 15 from the strain on the face plates when holding a member therebetween, and 15 thus allowing the face plates 7 to be easily removed when it is desired. The spring catches work automatically and allow the plates 7 to be snapped into place or to be quickly disengaged from the jaw members 20 5 and 6. The jaw members 5 and 6 are cut away with a beveled surface 25 on either end, which allows a tool, such as 26, illustrated in dotted outline in Figure 3, to be inserted between the end of the face plates 7 and the beveled edge of the members 5 and 6 to 25 pry the face plates 7 free from the spring catch 15, when it is desired to remove the same.

It is very desirable, in a machine shop or 30 other places, to have a vise with removable face plates so that various forms of face plates can be used, but it is highly essential to have a construction whereby the face plates can be easily and quickly removed. 35 This feature is accomplished in my invention, as the spring catches allow the face plates to be quickly and easily removed, still being held rigidly in position and under the tension of the spring 17, when the face plates 40 are attached to the main jaw members of the vise.

The face plate 7, illustrated in Figure 5, is formed with engaging points 27, which are cut up from the surface 8 of the plate 45 and are for the purpose of holding a leather, rubber or fiber block, such as 28. This construction allows a soft gripping surface to be used for delicate articles which are held in the vise A and by means of various sets 50 or pairs of different face plates 7, the ordinary vise can be used for practically any holding purpose, the spring catch holding means being the essential feature in the use of pairs of removable face plates.

55 The gripping member or jaw 5 is pivotally held to the body portion 2 of the vise A by means of the semicircular shank 29, having an enlarged head 30 which is also of a semicircular shape, and the rearwardly projecting portion 31 of the member 5 has a downwardly projecting circular shaped engaging flange 32, which engages a similar surface in the body portion 2 of the vise and thus holds the member 5 rotatable on a 60 comparatively large circle.

The outer surface of the flange 32 is serrated to form teeth 33. The teeth 33 are engaged by similar teeth formed in the movable head or gripping member 34, so as to hold the member 5 against rotation, when it 70 is desired, and to hold the same rigidly against turning in various positions, with the gripping face carried by the member 5 parallel to the gripping face carried by the member 6, or angularly to the same. A 75 threaded bolt 35, which is formed with an operating head 36 on one end, and having its other end swivelly connected to the member 34, is threaded in the rear portion of the member 2 and moves the gripping head or 80 member 34 into or out of engagement with the teeth 33 when the operating head 36 is rotated. Holes 37 are formed in the head 36, into which a suitable tool can be inserted to operate the threaded bolt 35, and thereby move the member 34 in either direction. The recess 38, in the member 2, holds the engaging head or member 34 in position in the rear portion 2 of the vise A. A 85 protecting plate 39 is secured by screws 40 to 90 the rear portion 31 of the jaw 5 and extends over the member 34 and teeth 33 to protect the same against filings, etc.

In the use of the vise A, when a member or article such as 41, which is angular in 95 shape, is engaged between the jaws 5 and 6 of the vise, the member 34 is disengaged from the teeth 33 to allow the jaw 5 to rotate so that its face plate 7 engages parallel with the angular surface of the member 41 and before the jaws of the vise A are caused to grip the member 41 tightly, the member 34 is operated to engage the teeth 33 to rigidly hold the jaw member 5 in 100 an angular position, as illustrated in Figure 2, whereupon the jaw members 5 and 6 can be drawn tightly against the article 41 to hold it in the vise. It will be noted that in gripping a member of this nature between the members 5 and 6 of a vise, especially where the member, such as 41, does not extend to the longitudinal center line, such as 42 of the vise, in a construction where one of the jaws, such as 5, is rotatable, unless the rotatable member 5 is rigidly gripped in the proper angular position in 110 relation to the member 6, by a means, such as the teeth 33 and the member 34, when the jaws 5 and 6 are drawn tightly against the member 41, the member 5 would rotate on its pivot until the points or edges 43 of the ends of the gripping plates 7, opposite to the member 41, come together. Thus, instead of holding or gripping the member 41 flatly against two angular sides, 115 it would be at the points 44 between the face plates 7, and would not be held rigid but would have a tendency to move pivotally in the jaw members 5 and 6. By the engaging means at the rear of the member 120 125 130

6, such as the teeth 33 and the engaging head 34, this is entirely overcome, and the rotatable jaw 5 is rigidly held in any angular position in relation to the member 6 5 or parallel thereto. This feature is highly important in my invention.

In accordance with the patent statutes I have described the principles of operation of my invention, together with the apparatus which I now consider to represent the best embodiment thereof, but I desire to have it understood that the construction shown is only illustrative and that the invention can be carried out by other means 15 and applied to uses other than those above set forth within the scope of the following claims:

1. In a vise having a movable gripping member, a removable face for said member, 20 pins rigidly attached to the back of said face, and spring catches for engaging said pins to hold said face to said gripping member.

2. In a vise of the class described, vise 25 jaws, a removable gripping face for said jaws, means rigidly secured to and projecting from the inner surface of said face, and spring means adapted to engage said projecting means to hold said face in operative position on said jaws.

3. In a vise of the class described, vise jaws, a removable gripping face for said 30 jaws, and an elongated tongue projected

parallel with the back of said face and formed integral therewith, a socket formed 35 in each of said jaws of the same shape as said tongue, and means for removably holding said face to either of said jaws.

4. In a vise having gripping members, a removable face plate for said members, an 40 elongated projection on the back of said face plate, holding pins projecting from said elongated projection and means for resiliently engaging said pins to removably hold said face plate to either 45 of said gripping members, said elongated projection holding said face plate against transverse or longitudinal movement on said gripping members.

5. A vise comprising a jaw, a removable 50 face plate for said jaw, a catch secured to said face plate and a pin movable within said jaw adapted to engage said catch to hold said face plate attached to the jaw.

6. In a vise of the class described, a grip- 55 ping member, a removable face plate for said member, an elongated tongue having rounded ends projecting from the back of said face plate, a socket formed in said gripping member of the same shape and 60 size as said tongue and a spring catch for holding said face plate freely removable from said gripping member for the purposes specified.

ANDREW STRAND.
